UNITED STATES PATENT OFFICE.

WILLIAM HENRY WILSON, OF NEW BEDFORD, MASSACHUSETTS.

LOOM-SHUTTLE.

37,524

Specification of Letters Patent. Patented Mar. 21, 1911.

Application filed September 4, 1909. Serial No. 516,189.

To all whom it may concern.

Be it known that I, WILLIAM H. WILSON, a citizen of the United States, and a resident of New Bedford, in the county of Bristol and State of Massachusetts, have invented a new and Improved Loom-Shuttle, of which the following is a full, clear, and exact description.

This invention relates to hand-threading loom shuttles and more particularly to the construction of the thread-engaging and delivering portions of the shuttle.

My invention is applicable to the ordinary type of shuttle in which a bobbin is supported within an opening in the body of the shuttle so as to deliver the thread off the end of the bobbin and through a delivery eye in the side of the shuttle.

One important feature of my invention involves a plate employed for preventing loops formed in the thread at the end of each pick, from swinging upwardly and out of the thread-receiving slot in the shuttle.

A further important feature involves the 25 tensioning device through which the thread passes to the delivery eye.

Reference is to be had to the accompanying drawings, forming a part of this specification, in which similar characters of reference indicate corresponding parts in all 30 the figures, and in which—

Figure 1 is a top plan view of the delivery end of a shuttle constructed in accordance with my invention; Fig. 2 is a side elevation thereof; Fig. 3 is a view similar to a portion of Fig. 1, the thread-retaining plate being removed; Figs. 4 and 5 are transverse sections on the lines 4—4 and 5—5, respectively, of Fig. 3; Figs. 6 and 7 are transverse sections on the lines 6—6 and 7—7, respectively, of Fig. 5; and Fig. 8 is a top plan view of the thread-delivering and tensioning device detached from the shuttle.

Various different forms of shuttles may 45 be constructed in accordance with my invention and various different changes made in the details, without departing from the spirit of my invention.

As illustrating one form which the invention 50 may assume, I have shown in the accompanying drawings, a shuttle 10, having an elongated central opening 11 adapted to receive the shuttle 12 and deliver the thread therefrom through a delivery eye in the side 55 of the shuttle. In the top of the shuttle, adjacent the delivery end, there is a substan-

tially vertical opening 13, extending down about half way through the shuttle and connected to the elongated opening 11 by a throat 14. The upper end of the opening 13 and the sides of the throat may be beveled or cut away, so as to avoid the sharp edges which might cut or sever the thread.

Extending transversely through the shuttle is a substantially cylindrical passage 16 of somewhat less diameter than the opening 13 and communicating with the lower end of the latter. A slot 16 extends from the opening 13 diagonally forward to one side of the shuttle and extends downwardly in depth to approximately the plane of the diameter of the transverse passage 15. A substantially horizontal slot 17 connects the lower or innermost portion of the slot 16 with the transverse passage 15 along approximately one-half the length of the latter.

In threading the shuttle, the thread is dropped through the throat 14, the opening 13 and the slot 16, to the slot 17, and then brought into the transverse passage 15, so that the thread extends out through one end of the latter. For preventing a loop in the thread from rising or ballooning out through the slot 16, I provide a thread-retaining member within the opening 13, and so constructed as to facilitate the entrance of the thread but to prevent its return movement. This thread-retaining means includes a plate 18 mounted upon a pin 19 and constituting a head for the latter. The pin extends down into the body of the shuttle and holds the plate in place, although by applying pressure to the under side of the plate, the plate and pin may be readily removed. The plate has one edge thereof curved to coincide with the side walls of the opening 13, so that said plate can not rotate about the pin as a center. Opposite this curved side, the plate has a projection or beak 20, terminating closely adjacent the side of the opening 13 but spaced therefrom a sufficient distance to permit the passage of the thread. The beak is curved downwardly as indicated in Fig. 4 and extends laterally past the opposite side of the throat 14, as indicated in Fig. 1. The plate has one side thereof substantially in alignment with the side of the slot 16, so that when the thread is brought down through the slot, the bend in the thread will pass along the edge of the plate to the beak 20 and slip past the latter to the under side.

As the beak is out of alignment with any por-

tion of the throat, it is evident that the thread in lifting up through the throat, will engage beneath the plate and can not escape. In place of a single plate 18 mounted on a single pin 19, I may, if desired, employ two plates mounted on two separate pins and having overlapping points spaced apart vertically to permit the passage of the thread therebetween. The overlapping of the points of the two plates would prevent the thread from rising vertically out of the slot.

Within the transverse passage 15 is mounted my improved tensioning and guiding device. This device is preferably in the form of a tube or barrel 21 fitting closely within the passage and removable lengthwise therefrom. The tube is formed from a single piece of sheet metal so cut and stamped as to form not only the body 22 of the tube, but also an end 23 and two transverse bars 24 and 25. The end 23 is provided with a slot 26 therein and extending from the lower edge of the end past the center of the end, so that the upper end of the slot constitutes the delivery eye of the shuttle. The entire lower portion of the tube adjacent the end 23, is cut away, so that adjacent this end the tube is only substantially semi-cylindrical in cross section. The bar 25 extends across the tube and has both ends secured to the edge of the semi-cylindrical portion, as is indicated particularly in Fig. 7. The bar 24 has a free end extending toward the point of the shuttle and spaced from the edge of the semi-cylindrical portion, as is indicated particularly in Fig. 6. The free end of the bar 24 fits into a recess in the wall of the shuttle and has its upper surface substantially in the plane of the lower surface of the slot 17, so that as the thread travels rearwardly through this slot, it will pass on to the upper side of the bar 24. The portion of the cylindrical passage 15, adjacent the end 23, is cut away or enlarged to form a curved passage 27 along the lower portion of the side of the end 23 toward the point of the shuttle and communicating with the slot 26 in said end 23. Thus, the thread in passing rearwardly through the slot 17 will pass beneath the bar 25 and over the bar 24 and thence around a portion of the edge of the end 23 to the lower end of the slot 26. The end 23 is spaced inwardly a slight distance from the outer surface of the shuttle, so that after the thread has once passed through to the position indicated in Fig. 5, it cannot pass out of the lower end of the slot 26. The bar 24 holds the thread adjacent the upper end of the slot and nearer the center of the end.

The tube upon its upper side and intermediate its ends has an opening 28 communicating with the aperture 13 in the body of the shuttle, and from this opening a slot 29 leads to the edge of the semi-cylindrical

portion and to the lower end of the slot. Thus, the thread in passing down through the slot 16, comes to the end of the slot and thence travels through the latter to opening 28. The slot leads into the opening 28 from the end opposite to the end, so that as the thread is drawn out through the delivery eye there is no tendency for the thread to accidentally escape through the slot 29. The tube at the end opposite to the end 23, has the edges of the sheet metal forming the tube spaced apart a short distance and provided with depending projections or teeth 30, adapted to enter the lower wall of the transverse passage 15 and hold the tube against accidental displacement.

In threading the shuttle, it is merely necessary to drop the thread through the slot 16 and draw it back through the slot 17. The thread automatically slips over the beak 24 and passes through the slot 29 and beneath the edge of the tensioning and guiding device 21. The thread slips beneath one edge of the end 23, so that it passes between the two substantially horizontal guiding members 24 and 25 and between the two substantially vertical guiding members at opposite sides of the slot 26. The shuttle cannot become unthreaded and the thread cannot become accidentally displaced or fail to operate properly.

Having thus described my invention, I claim as new and desire to secure by Letters Patent:

1. A loom shuttle having a spindle recess, an aperture extending into the body of the shuttle adjacent the end of the spindle recess, a slot extending from said aperture forwardly and outwardly to the side of the shuttle, a transverse passage leading from said aperture to the side of the body, a slot connecting said passage and the lower portion of said first-mentioned slot, and a tension device within said passage and including two transverse bars extending across the passage, one disposed above said first-mentioned slot and the other disposed below the same.

2. A loom shuttle having a transverse passage through the wall thereof and through which the thread passes, and a tensioning device within said passage and including two bars extending transversely across the passage, and a slot leading through the wall of the shuttle to said passage and terminating above one of said bars and below the other bar.

3. A loom shuttle having a transverse passage, a slot communicating therewith, and a tensioning device within said passage and including a transverse bar also extending across the passage and constituting a continuation of one side of said slot and a second transverse bar forming a continuation of the opposite side of said slot.

4. A loom shuttle having a tensioning device formed of sheet metal and bent to substantially semi-cylindrical form, a bar connecting the opposite sides of said semi-cylindrical portion, and a second bar supported at one side and terminating free from the opposite side, the body of the shuttle having a slot through which the thread may pass to the space between said bars.
10. 5. A loom shuttle having a thread-tensioning and delivering device, including a sheet metal member having a portion thereof bent to substantially semi-cylindrical form, a slotted end wall integral therewith and two transverse bars, one of them terminating at one edge of said semi-cylindrical portion and the other bar spaced from said edge to permit the passage of the thread to the space between said bars.
15. 6. A loom shuttle having a body portion provided with an elongated opening to receive the bobbin, an aperture extending into top of the shuttle, a throat connecting elongated opening and said aperture serving for the passage of thread and a slot extending forwardly and outwardly from said aperture to the side of the shuttle, a plate having a depending pin extending into the body of said shuttle for detachably supporting the plate and having inwardly-curved projection extending across the aperture beyond the end of the slot.
20. 7. A loom shuttle having a thread-tensioning and delivering device, including a sheet metal member bent at one end to substantially tubular form and at the opposite end to substantially semi-cylindrical form, two transverse bars carried by the semi-cylindrical portion for receiving the thread between.
75. 8. A loom shuttle having a thread-tensioning device substantially tubular in form at one end and substantially semi-cylindrical at the other and having a transverse wall at the last-mentioned end and provided with a central aperture constituting a thread-delivering eye.
90. 9. A loom shuttle having a spindle recess, an aperture extending into the body of the shuttle adjacent the end of the spindle recess, and a slot extending from said aperture forwardly and outwardly to the side of the shuttle, a plate disposed within said recess and having one side thereof substantially in alignment with the side of said slot and having one end thereof extending
- beyond the end of said throat, and curved downwardly, and a pin extending into the shuttle body at one side of the throat and out of the path of the thread for detachably supporting said plate.
10. 10. A loom shuttle having a body provided with an opening therein, and a thread guide within said opening and formed of sheet metal bent to substantially tubular form, the adjacent edges of said sheet metal being bent outwardly to resiliently engage with the body of the shuttle to prevent longitudinal or rotative movement of the guide, and the sheet metal at one end being bent at substantially right angles to the general direction of the tubular portions and having an opening through which the thread may pass.
75. 11. A loom shuttle having a spindle recess, an aperture extending into the body of the shuttle adjacent the end of the spindle recess, a throat connecting said aperture and said recess, and a slot extending from said aperture forwardly and outwardly to the side of the shuttle, a plate disposed within said recess and having one end thereof extending beyond the end of said throat, and a pin extending into the shuttle body at one side of the throat and out of the path of the thread, for detachably supporting said plate.
12. 12. A loom shuttle having a thread tensioning device formed of sheet metal bent to substantially tubular form and having portions of the adjacent edges of said sheet metal bent outwardly to constitute separate teeth or projections adapted to engage with the body of the shuttle to prevent longitudinal or rotative movement of said device within said body.
95. 13. A loom shuttle having a body provided with an opening therein, and a thread guide within said opening, said thread guide being formed of sheet metal bent to substantially tubular form, the adjacent edges of said sheet metal being bent outwardly and presenting a tooth or projection in resilient engagement with the body of the shuttle to prevent longitudinal or rotative movement of said guide.
100. In testimony whereof I have signed my name to this specification in the presence of two subscribing witnesses.
